UNITED STATES PATENT OFFICE.

WILLIAM H. BEVANS, OF WASHINGTON, DISTRICT OF COLUMBIA.

SIGHT FOR ORDNANCE.

SPECIFICATION forming part of Letters Patent No. 642,670, dated February 6, 1900.

Application filed May 12, 1898. Serial No. 680,444. (No model.)

To all whom it may concern:

Be it known that I, WILLIAM H. BEVANS, a citizen of the United States, residing at Washington, District of Columbia, have invented 5 certain new and useful Improvements in Sights for Ordnance; and I do hereby declare the following to be a full, clear, and exact description of the invention, such as will enable others skilled in the art to which it app- 10 pertains to make and use the same.

This invention relates to sights for ordnance; and the primary object thereof is to provide an improved mechanism whereby the sight may be quickly and accurately adjusted 15 and to minimize the number of parts employed in such mechanisms, thus simplifying the same and effecting a reduction in weight and in cost of manufacture.

The invention also consists in certain other 20 improvements, which will be fully set forth in the following specification, particularly pointed out in the claims, and clearly illustrated by the accompanying drawings, in which—

25 Figure 1 is a top plan view of my improved sight in position upon the trunnion of a gun. Fig. 2 is a side elevation of the same. Fig. 3 is transverse sectional view taken on the line α of Fig. 2. Fig. 4 is a similar view taken on line α of Fig. 3. Fig. 5 is a top plan view showing my sight provided with means for effecting the lateral adjustment thereof. Fig. 6 is a side elevation of the same. Fig. 7 is a transverse sectional view 30 on line α of Fig. 6. Fig. 8 is a similar view taken on the line γ of the same figure. Fig. 9 is a top plan view with the telescope and elevating-drum removed. Fig. 10 is a side elevation of the same.

35 I have illustrated and described my invention in the present instance in connection with that class of sights known as "telescope-sights," but do not desire to limit the same to that class, as it is equally applicable to other 40 forms of sights.

Referring now more particularly to Figs. 1, 2, 3, and 4 of the drawings, 1 designates a supporting-plate having the laterally-extending trunnion-bearings 2 formed at one end 45 thereof and at its opposite end the laterally-extending boss 3. A telescope 4, such as is ordinarily in telescope-sights, is pivotally

mounted upon said supporting-plate through the medium of the trunnions 5, projecting from a trunnion-band 6, secured about the body or main tube of the telescope and engaging said trunnion-bearings, in which they are retained by caps 7. A shaft 8 is threaded into boss 3 and at its outer end is reduced and threaded, as at 9, and at the inner end 60 of said threaded portion formed with an annular shoulder 10.

Mounted upon shaft 8 is an elevating disk or drum 11, the hub of which is counterbored to receive shoulder 10 of said shaft. A suitable clamping-nut 12 is provided upon the threaded end of the shaft and is adapted to lock the drum or disk from movement upon said shaft after the sight has been adjusted. Formed in said disk or drum, about the center thereof, is a spiral slot 13, into which projects a pin 14, carried by an elevating-band 15, also secured upon the body of the telescope. This pin projects from a laterally-extending lug 16 upon said elevating-band, 75 which lug is formed with a flat bearing-surface engaging the inner face of the drum or disk, while a similar lug 17 is formed on the opposite side of the elevating-band, the bearing-surface of which engages a vertical guide 80 extension 18, formed on the supporting-plate. Thus as the telescope is elevated and depressed it is guided in its movement by the engagement of said lugs with the inner face of the disk and guide extension. The elevat- 85 ing disk or drum is provided about the outer edge of the spiral slot with a scale, the graduations of which are brought into coincidence, with an index or pointer upon the end of pin 14 as said disk or drum is rotated. 90

When it is desired to adjust the telescope to insure the proper elevation of the gun for an object at a distance of, say, two thousand yards, the elevating disk or drum is rotated, its periphery being milled to facilitate the 95 same, until the two thousand yards graduation of the scale coincides with the index upon the pin, when the sight will be elevated the requisite number of degrees. Thus it will be seen that the elevation and depression of the telescope are effected through the coaction of the pin carried thereby and the spiral slot of the elevating-disk. Owing to the fact that the pin carried by the sight is at all times

above the axis of the elevating-disk the weight of the sight will cause the same to be retained in its adjusted position without the use of the clamping-nut, the latter not being essential, but provided as a safeguard to positively lock the sight from any movement which might possibly occur from the shock or vibration incident to the firing of the gun to which it is attached.

10 Through the medium of the spiral elevating-slot an increased scale-surface is provided, so that the graduations may be placed quite a distance apart, thus permitting the sight to be quickly and accurately adjusted by facilitating the reading of the scale and necessitating a considerable movement of the elevating-disk to elevate or depress the telescope a single degree.

For attaching the sight to the gun I place 20 at any suitable and preferred position upon the latter (it being illustrated in the present instance as positioned upon the trunnion of the gun) a bracket 19, having an open-ended dovetailed groove formed therein and secure 25 to or form integral with the supporting-plate a dovetailed plate 20, which slides in the groove of the bracket, thus positioning the sight upon the gun. The supporting-plate is formed with a hollow boss 21, which opens 30 through the dovetailed plate and in which a plunger 22 is positioned, the same being held normally projected from said plate by a coiled spring within the boss. The projecting end of this plunger enters an opening formed in 35 the bracket as the sight is positioned upon the gun, and in removing the sight from the gun the plunger is retracted, it being provided with a suitable knob for that purpose. It will be noticed that the face of the dovetailed 40 plate 20 is inclined, and the same is so formed for the purpose of giving the sight the proper set in order to compensate for the drift or lateral deviation of the gun.

In Figs. 5 to 10, inclusive, my improved 45 sight is shown provided with a lateral adjustment in addition to the vertical adjustment before described, and through the medium of this construction the sight may be adjusted laterally and also be readjusted to proper position with respect to the gun should it become accidentally displaced from any cause. In the sight illustrated in said figures the supporting-plate is provided at its upper edge with a laterally-projecting shelf 23, upon 50 which trunnion-bearings 2 are swiveled through the medium of a pivot pin or stem 24, depending centrally from said bearings and having its bearings in the shelf, through 55 which it depends and receives a nut 25 on its projecting end. An arm 26 extends rearwardly from the trunnion-bearings, and upon this arm, adjacent to its free end, the boss 3 is formed, which carries the shaft of the elevating-drum. The mounting of the telescope 60 upon the trunnion-bearings and the mechanism for elevating and depressing it have been described hereinbefore, the only difference in

construction between the sight first described and the one now under consideration being the slight change incident to the swiveling of the telescope and its elevating and depressing mechanism to the supporting-plate. A pin 27 depends from the free end of the arm 26 and moves in a curved slot 28, formed in the shelf, and is provided upon its projecting 75 end with a clamping-nut 29, whereby the telescope may be locked in its adjusted position. A boss 30 is raised about said slot, upon which said arm moves, and a scale may be provided thereon with which an index upon the arm 80 may coact, so that the telescope may be readily adjusted the desired number of degrees to the right or left.

It will be apparent that the lateral movement of the telescope could be effected in 85 a number of different ways other than that here shown and described—as, for instance, through the medium of a rack and pinion—and I therefore do not desire to limit my invention to the details of construction herein set forth for accomplishing such adjustment.

The guide extension, which guides the telescope in its elevation and depression, is carried by the inner end of the drum-shaft boss 95 instead of being formed on the supporting-plate, as in the first construction described.

The mounting of the sight upon the gun has been hereinbefore described, the plunger 22 in the present instance being located below the rearwardly-extending arm, so that ready access is afforded to the knob for retracting the same. The dovetailed plate, however, is not inclined in the present construction; but the proper set of the sight to 105 compensate for the lateral deviation of the gun is provided for by forming the trunnion-bearings at an angle to the stem or pivot-pin thereof, so that the sight is not only supported at the necessary angle to the gun, but the 110 axis thereof retains the same relative position with respect to the gun throughout the lateral movement of the sight, which would not be the case were the supporting-plate and shelf set at an inclination, in which event the 115 axis of the sight would rise or lower during lateral movement.

As stated at the beginning of the specification, the construction described and illustrated is not limited to use upon telescope-sights, and it will be apparent that a sight-bar might be readily substituted for the telescope without materially altering the details of construction.

Having thus fully described my invention, 125 what I claim as new, and desire to secure by Letters Patent of the United States, is—

1. In an adjustable sight for ordnance, the combination with an elevating member formed with a cam-surface and having a scale following the contour of said surface; of an elevating member engaging said surface and carrying an index coacting with said scale, substantially as described.

2. In an adjustable sight for ordnance, the combination with an elevating member formed with a spiral elevating-surface and having a scale following the contour of said surface, of an elevating member engaging said spiral surface and carrying an index coacting with said scale, substantially as described.
3. In an adjustable sight for ordnance, the combination with an elevating member formed with a cam-surface and having a scale placed along the edge thereof, of an elevating member engaging said cam-surface and carrying an index coacting with said scale, substantially as described.
4. In an adjustable sight for ordnance, the combination with an elevating-drum formed with a cam-elevating surface and having a scale following the contour of said surface, of an elevating member engaging said cam-surface and carrying an index coacting with said scale, substantially as described.
5. In an adjustable sight for ordnance, the combination with an elevating-drum formed with a cam-elevating surface and having a scale following the contour of said surface, of an elevating member carried by the sight engaging said surface and provided with an index coacting with the scale, substantially as described. 25
6. In an adjustable sight for ordnance, the combination with an elevating member formed with a cam-slot and having a scale arranged along the edge thereof, of an elevating member projecting into said slot and carrying an index coacting with said scale, substantially as described. 30
- 35

In testimony whereof I affix my signature in presence of two witnesses.

WILLIAM H. BEVANS.
